Primary Examiner — Karen S Acker(74) *Attorney, Agent, or Firm* — Dority & Manning, P.A.(57) **CLAIM**

The ornamental design for a fabric, as shown and described.

DESCRIPTION

FIG. 1 is a front view of a fabric showing our new design; FIG. 2 is a perspective view thereof; and, FIG. 3 is an enlarged detail view of the area circumscribed by the two arrowed lines labeled 3 within FIG. 1. The broken lines surrounding FIGS. 1 and 2 depict the boundaries of the claim and form no part thereof. The broken line around FIG. 3 illustrates the boundary of the detail area and forms no part of the claimed design.
